UNITED STATES PATENT OFFICE.

SAMUEL F. JOOR, OF MORGAN PARK, ILLINOIS, ASSIGNOR TO THE JEFFREY MANUFACTURING COMPANY, OF COLUMBUS, OHIO, A CORPORATION OF OHIO.

CONVEYER.

1,057,556.

Specification of Letters Patent.

Patented Apr. 1, 1913.

Application filed December 17, 1907. Serial No. 406,957.

To all whom it may concern:

Be it known that I, SAMUEL F. JOOR, a citizen of the United States, residing at Morgan Park, in the county of Cook and 5 State of Illinois, have invented certain new and useful Improvements in Conveyers, of which the following is a specification, reference being had therein to the accompanying drawing.

10 My invention relates to conveyers comprising a series of carriers and particularly to endless conveyers of the type generally known as swinging tray elevators. In this class of conveyers an endless chain or cable 15 traveling in vertical paths and around a sheave or sprocket wheel at each of the upper and lower limits of its course, supports a series of carriers. These carriers receive packages or bundles of various description 20 at any one of several stories or floors of the building in which the conveyer is installed and deliver at any floor.

25 My invention has two objects in view: first, automatic means for preventing the placing of a load in position to be received by the moving carrier when the carrier already has a load upon it; second, automatic means whereby the operator when loading a carrier can determine the floor at which the 30 load will be discharged.

Other minor objects will appear from a reading of the following description, in connection with the drawings of which;

35 Figure 1 is a fragmentary vertical, sectional view of a building through the conveyer shaft. Fig. 2 is a similar sectional view taken in a plane at right angles to that of Fig. 1. Fig. 3 is an enlarged horizontal, sectional view across the conveyer shaft 40 taken along the line 3—3 of Figs. 2 and 4. Fig. 4 is an enlarged vertical section showing one complete set of mechanisms as provided at each floor, the view being taken along the line 4—4 of Fig. 3 in the direction 45 of the arrow b. Figs. 5 and 6 are enlarged detail views of the adjustable contact roller. Fig. 7 is an enlarged detail view of the device for locking the loading platforms in position. Fig. 8 is a vertical sectional enlarged view taken along the line 8—8 of Fig. 3 in the direction of the arrow a. Fig. 9 is an enlarged vertical sectional view taken along the line 9—9 of Fig. 4 in the direction of the arrow c. Fig. 10 is an enlarged horizontal sectional view showing the

manner in which the carriers are suspended from the chain. Fig. 11 is a perspective view of the central carrier finger 42^a and adjacent parts. Fig. 12 is a detail view of the retaining device for the loading mechanism controlling lever.

21 to 26 indicate the respective floors of a six-story building. 27, 27 are two sprocket cables, chains or ropes which pass over the sprocket wheels 28, 28, at a point above the 65 top floor and under the sprocket wheels 29, 29, at a point below the first floor.

The wheels 28, 28 are suitably mounted in the supporting framework 30 and are driven by pinions 31, 31, rigidly mounted on the 70 shaft 32 which in turn is driven from any suitable source of power to which it is connected by the power-transmitting devices indicated generally by 33. The lower wheels 29, are mounted in the framework 34 in a 75 manner to provide for the takeup of slack in the cables.

The carriers 35, comprise the grid-like tray 36 carried by the suspension bars 37 which are pivotally hung from the short 80 shafts 38, carried in suitable bearings by the chain or cable. Upon the short shafts 38 are mounted the guide wheels or rollers 39 and at the lower end of the suspension bars 37, similar guide wheels 40 are mounted. 85

The angle irons 41, serve as guide-rails for these guide wheels and are suitably curved at their ends, so that the trays are moved in a fixed vertical path, without oscillation about their axis of suspension while 90 traveling in the upward and downward paths of their course, and are allowed to swing freely when making the upper and lower turns.

The tray proper consists of the U-shaped 95 metal frame piece 41', rigidly secured to the suspension bars 37, the parallel wooden fingers 42 rigidly secured to the frame piece, and the end plates 42' bolted to the frame piece, and suspension bars.

I will now describe the automatic means 100 duplicated upon each floor by which I prevent the placing of a package in position to be engaged by the fingers 42 of a carrier, when such carrier is already loaded. In Fig. 4, 43 is a doorway or opening for obtaining access to the conveyer on the loading side, which is the side on which the conveyer moves upwardly.

44 is a loading platform, consisting of the 110

U-shaped frame bar 45 and the parallel fingers 46, rigidly secured thereto and spaced to permit the fingers of the moving carrier-trays to pass between them in the manner shown. This loading platform is hinged in the plane of the doorway 43 at 47 to hinge pins 48 projecting from fixed parts of the building. By means of the links 49 each pivoted at one end to the outer ends of the 10 U-shaped frame bar 45 and at the other to one end of one of the levers 50, which are pivoted to fixed parts of the building at 51, 51, the loading platform can be raised or lowered. The counter weights 52 on 15 the ends of the levers 50, opposite the pivotal connection with link 49, act to hold the platform in a vertical position against the stops 53, as indicated in dotted lines, Fig. 4. The yieldable spring detent or 20 catch 53' holds the lever and platform in a definite vertical position.

To load a carrier a package or bundle is put upon the stationary stand 54, the handle 55 of either one of the levers 50 is 25 raised throwing the platform to a horizontal position, and the bundle pushed by the operator onto the platform. The next carrier will lift the bundle from the platform as its fingers pass between the platform 30 fingers, and the weights 52 will cause the platform to resume its normal vertical position.

To prevent the operators from placing a bundle in position on the loading platform 35 44 when the next approaching tray is already loaded, with the result of crushing the lower bundle or causing the upper one to fall down the conveyer shaft, the platform 44 is automatically locked in position 40 while a carrier thus loaded is the next approaching one.

The plunger 56, held normally out of engagement with the socket 57 in the free end of one of the fingers 46 by the spring 58, is moved 45 into engagement when the solenoid 59 is electrically energized. One terminal of the solenoid is connected to one of two electrical main wires 68 and 69, which lead from the positive and negative terminals of a 50 suitable source of electric current, as shown diagrammatically in the drawings. The other terminal is connected with the guide-rails 41.

Pivoted to the outer end of one or more 55 of the moving tray fingers 42, preferably of the central finger 42^a, is a channel-shaped covering piece 60 with its depending flanges 61 lying on either side of the finger. A light compression spring 62 is secured at 60 one end to the under side of this covering piece 60 and at the other end to the top of the finger 42^a near its inner end. On the under side of the free end of the piece 60 is mounted one of a pair of electrical contacts 63, 64, the other contact 64 being di-

rectly beneath it on the finger 42^a. The wire 65 connects any part of the metal cover piece 60 with the metal tray frame 41'. The electrical contact device 66 is mounted upon the outer vertical face of the tray frame 41' and insulated therefrom. This contact may be a metal button, as shown, or a suitably mounted roller, and is electrically connected to the contact button 64 by the conductor wire 73. The contact strip 67 extends from the level of one landing or a point shortly above a landing down below the floor a distance somewhat greater than the distance between two trays. This contact strip is mounted upon suitable framework 68 from which it is insulated, and is electrically connected to the second one of the two main current supply wires 68, 69 above mentioned by the conductor wire 74. When a loaded ascending carrier reaches a point where its contact device 66 engages the contact strip 67 a circuit is established between the positive and negative supply wires 68 and 69 through the conductor wire 70, the solenoid 59, conductor wire 71, guide-rails 41, guide 90 wheels 40, the carrier frame 41', conductor wires 65, cover piece 60, contact key 63, 64, conductor wire 73 contact device 66, strip 67, and conductor wire 74.

The plunger is moved into engagement 95 with the socket in the free end of the central finger of the loading platform which is thereby locked in position until the loaded tray has reached a point where the contact device 66 breaks engagement with the 100 contact strip 67. On the other hand when an unloaded carrier approaches a landing the key 63, 64 is held open by the spring 62, no circuit is established and the plunger is held out of engagement with the socket in 105 the finger of the loading platform by the spring 58 and the lever 50 can be operated to throw the loading platform into a horizontal position.

I have also devised means whereby the 110 operator when loading the carrier may determine the floor at which it shall automatically unload. Referring to Fig. 9, to the right hand side of Fig. 8 and to the left-hand side of Figs. 3 and 4, a discharging 115 platform 74' comprises the parallel fingers 75, spaced to permit the carrier fingers to pass between them and the U-shaped frame bar 76 to which the fingers are rigidly secured. To the frame bar are secured the 120 ends of the shafts 77, 78 which are mounted in the bearings 79, 80. Rigidly secured to these shafts are the levers 81 at the outer ends of which are the counter-weights 82. Also rigidly secured to the shaft 78 is the 125 spur gear wheel 83 which meshes with the rack bar 84 carried by the plunger 85 operated by the solenoid 86. The limit of upward movement of the discharging platform is determined by the links 87, 87, 88, 88, 130

each of the links 87 being pivotally secured at one end to one end of the frame 76 of said discharging platform and each of the links 88 being pivotally secured at one end to fixed parts of the building, each pair of links being pivoted together at their other ends. Upon one of the side plates of the carrier is mounted the gear wheel 89 (see Figs. 5 and 6), manually operated by means of the hand-lever 90 and meshing with the rack bar 91, carrying the roller contact 92. In front of the gear wheel 89 is a dial upon which are marked the numbers 1, 2, 3, etc., corresponding to the floors of the building. Mounted upon stationary parts of the walls of the conveyer shaft are contact strips 93^a, 93^b, etc., which are engaged by the contact roller 92. These contact strips are connected to one of the current feed wires, heretofore mentioned, by conductor wire 94, and conductor wire 95 electrically connects the guide rails 41 with the solenoid 86, the other terminal of which is connected to the other current feed wire by the conductor 96. Each of the contact strips 93^a, 93^b extends from a point between two landings down to a point just below the lower of the said two landings, no two of said contact strips being in vertical alinement with each other.

When a carrier, the dial of which has been set at Fig. 5 by the operator, as he placed thereon the load during its ascent, reaches the point during its descent at which the roller 92 comes into contact with the strip 93^b when intermediate of the fifth and sixth floors, circuit will be completed through conductor wire 94, contact strip 93^b, contact roller 92, carrier frame, guide rails 41, conductor wire 95, solenoid 86 and conductor wire 96, and the plunger of the solenoid will be operated to raise the fingers of the platform 74', in a position to discharge the bundle from the carrier tray 36.

What I claim is:

1. In a conveying system, guide mechanism, a series of carriers, means for propelling said carriers along said guide mechanism, a series of loading stations, loading mechanism at the stations, means for locking each of the loading mechanisms against operation, and means on each of the carriers designed when the carrier is loaded to automatically put each of said locking means into action at a corresponding predetermined part of the path of said carriers.

2. In a conveying system, guide mechanism, a series of carriers, means for propelling said carriers along said guide mechanism, a series of loading stations, loading mechanism at the stations, means for locking each of the loading mechanisms against operation, and means on each of the carriers operable by a load carried thereby, designed

to automatically put each of said locking means into action at a corresponding predetermined part of the path of said carriers.

3. In a conveying system, guide mechanism, a series of carriers, means for propelling said carriers along said guide mechanism, a series of loading stations, loading mechanism at the stations, means for automatically causing each loading mechanism to resume its normal position after each loading operation, means for locking each of the loading mechanisms against operation, and means on each of the carriers operable by a load carried thereby, designed to automatically put each of said locking means into action at a corresponding predetermined part of the path of said carriers.

4. In a conveying system, guide mechanism, a series of carriers, means for propelling said carriers along said guide mechanism, a series of loading stations, loading mechanism at the stations, means for locking each of the loading mechanisms against operation, and a series of devices located at predetermined parts of the path of said carriers, and means on each of the carriers operable by a load carried thereby coöoperating with each of the aforesaid series of devices to automatically throw the corresponding locking means into action.

5. In a conveying system, guide mechanism, a series of carriers, means for propelling said carriers along said guide mechanism, a series of loading stations, loading mechanism at the stations, means for locking each of the loading mechanisms against operation, and a series of devices located at predetermined parts of the path of said carriers, and means on each of the carriers operable by a load carried thereby coöperating with each of the aforesaid series of devices to automatically throw the corresponding locking means into action to maintain said locking means in action until the carrier has past the corresponding loading station and immediately thereupon throw out of action said locking means.

6. In a conveying system, guide mechanism, a series of carriers, means for propelling said carriers along said guide mechanism, a series of loading stations, loading mechanism at the stations, an electro-magnetic device, mechanical means operable by said electro-magnetic device for locking each of the loading mechanisms against operation, a pair of extended electrical contacts along the path of the carriers corresponding to and in advance of each loading station, contacts upon each carrier engaging therewith respectively, a contact key upon the carrier operable by a load carried thereby, a source of electric current, and wiring whereby the current source, electro-magnetic device, extended electrical contacts, pair of contact devices mounted on the carrier, and

the contact key are in series in one electrical circuit.

7. In an endless conveying system, vertically arranged guide mechanism, turning devices at the upper and lower ends thereof, an endless chain or cable passing around said turning devices and along said guide mechanism, carriers attached at regular intervals thereto, a series of loading stations, loading mechanism at the stations, means for locking each of the loading mechanisms against operation, and a series of devices each located in advance of a corresponding loading station a distance approximately equal to the interval between two successive carriers, and means on each of the carriers operable by a load carried thereby, designed to coöperate with each of the said series of devices to automatically put the corresponding locking means into action at a corresponding predetermined part of the path of said carriers.

8. In an endless conveying system, vertically arranged guide mechanism, turning devices at the upper and lower ends thereof, an endless chain or cable passing around said turning devices and along said guide mechanism, fork-like carriers attached at regular intervals thereto having a plurality of horizontal fingers, a series of loading stations, fork-like loading mechanism at the stations having a plurality of horizontal fingers interspaced with respect to the carrier fingers and adapted to occupy two positions one horizontal with its general outline coinciding with the cross section of the path of the carriers and the other entirely removed from the lines of travel of the carriers, means for withdrawing each loading mechanism from the former to the latter position after the operation of loading, means for locking each of the loading mechanisms in the second position, and a series of devices each located in advance of a corresponding loading station a distance approximately equal to the interval between two successive carriers, and means on each of the carriers operable by a load carried thereby, designed to coöperate with each of the said series of devices to automatically put the corresponding locking means into action at a corresponding predetermined part of the path of said carriers.

9. In an endless conveying system, guide mechanism, an endless chain or cable moving through a path determined by said guide mechanism and controlled in its motion thereby, carriers attached at regular intervals thereto, a series of loading stations along the path of the endless conveyer, loading mechanism at each station capable of having two positions of adjustment, one in the path of articles being conveyed by the carriers and the other out of said path, locking mechanism for each loading mecha-

nism to hold it in its latter position, and control mechanism upon the carriers adapted to automatically operate the said locking mechanism while a loaded car is passing a loading station.

10. In a vertically moving conveyer of the class described having a series of carrier trays spaced at regular intervals, unloading stations, an unloading tray at each station capable of having two positions of adjustment, one in the path of articles conveyed by the carriers and the other out of said path, power means for moving said unloading tray from the latter to the former position, and control mechanism upon each carrier adapted to operate the power means, and automatic means independent of the said carrier trays for returning said unloading tray to the aforesaid latter position.

11. In a conveying system, a guide mechanism, a series of carriers, means for propelling said carriers along said guide mechanism, a series of unloading stations, unloading mechanism at each of said stations, means continuously tending to move the unloading mechanism to an inoperative position, adjustable means on each carrier adapted in each position of adjustment to move one of said unloading mechanisms into an operative position, and means for adjusting said adjustable means.

12. In a conveying system, a guide mechanism, a series of carriers, means for propelling said carriers along said guide mechanism, a series of unloading stations, unloading mechanism at each of said stations, means continuously tending to move the said unloading mechanism into an inoperative position, adjustable means on each carrier adapted in each position of adjustment to move one of said unloading mechanisms into an operative position, and means likewise on said carrier for adjusting said adjustable means.

13. In an endless conveying system, an endless cable or chain, a guide mechanism therefor, means for driving the cable or chain, carriers attached at regular intervals to said cable or chain, a series of unloading stations, unloading mechanism at each of said stations, means continuously tending to move the said unloading mechanism to an inoperative position, a device for moving said unloading mechanism to an operative position, a series of devices out of alignment with one another with respect to the lines of travel of the conveyer one at each unloading station, and adjustable means on the carriers coöperating with any one of said devices to set in operation any one of said unloading mechanisms, and means for adjusting said adjustable means.

14. In a vertical moving conveyer of the class described having a series of carrier trays spaced at regular intervals, unloading

stations, an unloading tray at each station capable of having two positions of adjustment, one in the path of the conveyer and the other out of said path, power means for moving said unloading tray from the latter to the former position, automatic means independent of the said carrier trays for returning said unloading tray to the aforesaid latter position, a series of devices out of alinement with one another with respect to the lines of travel of the carriers, and an adjustable means on each of the carriers co-operating with any one of the aforesaid series of devices to move the corresponding unloading platform into the path of the carrier.

15. In a vertically moving conveyer of the class described having a series of carriers trays spaced at regular intervals, unloading stations, an unloading tray at each station capable of having two positions of adjustment, one in the path of the conveyer and the other out of said path, power means for moving said unloading tray from the latter to the former position, automatic means independent of the said carrier trays for returning said unloading tray to the aforesaid latter position, a series of devices out of alinement with one another with respect to the lines of travel of the carriers, an adjustable means on each of the carriers co-operating with any one of the aforesaid series of devices to move the corresponding unloading platform into the path of the carrier, and means for adjusting said adjustable means.

16. In a vertically moving conveyer of the class described having a series of carrier trays spaced at regular intervals, unloading stations, an unloading tray at each station capable of having two positions of adjustment, one in the path of the conveyer and the other out of said path, power means for moving said unloading tray from the latter to the former position, automatic means independent of the said carrier trays for returning said unloading tray to the aforesaid latter position, a series of devices out of alinement with one another with respect to the lines of travel of the conveyer, each located in advance of a corresponding unloading station a distance less than the distance between two successive carriers, and an adjustable means on each of the carriers co-operating with any one of the aforesaid series of devices to move the corresponding unloading platform into the path of the carrier.

17. In a vertically moving conveyer of the

class described having a series of carrier trays spaced at regular intervals, unloading stations, an unloading tray at each station capable of having two positions of adjustment, one in the path of the conveyer and the other out of said path, power means for moving said unloading tray from the latter to the former position, automatic means independent of the said carrier trays for returning said unloading tray to the aforesaid latter position, a series of devices out of alinement with one another with respect to the lines of travel of the conveyer, each located in advance of a corresponding unloading station a distance less than the distance between two successive carriers, and an adjustable means on each of the carriers co-operating with any one of the aforesaid series of devices to move the corresponding unloading platform into the path of the carrier, to maintain it in said position until said carrier has passed the corresponding unloading station.

18. In an endless conveyer system, an endless cable or chain, a guide mechanism therefor, means for driving the cable and chain, carriers attached at regular intervals to said cable or chain, a series of unloading stations, unloading mechanism at each of said unloading stations adapted to cause a carrier to unload its package or bundle, mechanical electro-magnetic means for operating said unloading mechanism, a series of extended electrical contacts out of alinement with one another with respect to the lines of travel of the conveyer each commencing at a point in advance of its corresponding unloading mechanism by a distance less than the interval between two successive carriers and extending beyond said corresponding unloading mechanism, an adjustable electrical contact upon each of said carriers adapted to engage one of said extended electrical contacts in a corresponding position of adjustment, a source of electric current and a system of connecting conductor wires, whereby when any one of the said extended electrical contacts is in engagement with the carrier contact, circuit is established having in series the source of current, and the mechanical electro-magnetic means.

In testimony whereof I affix my signature, in presence of two witnesses.

SAMUEL F. JOOR.
